UNITED STATES PATENT OFFICE.

JAMES ALBERTS, OF DALLAS, TEXAS.

CABLE REELING AND PULLING TRUCK.

1,256,093.

Specification of Letters Patent. Patented Feb. 12, 1918.

Application filed April 25, 1916. Serial No. 93,420.

To all whom it may concern:

Be it known that I, JAMES ALBERTS, citizen of the United States, residing at Dallas, in the county of Dallas and State of Texas, have invented certain new and useful Improvements in Cable Reeling and Pulling Trucks, of which the following is a specification.

This invention pertains to new and useful improvements in cable reeling and pulling trucks.

Cable such as is used in telephone and telegraph systems is usually coiled on large spools or reels and in this manner transported to the place where it is to be pulled into service. Various devices and apparatuses have been evolved for transporting the reels from the ware house to the point where the cable is to be installed and means has also been employed for winding and unwinding the cable; but so far as I am aware none of these devices have come into wide use and in each instance have either been found unsatisfactory or fallen short of the mark.

In carrying out the invention I first provide a portable structure which may be easily propelled or drawn over roads or streets. On this structure I provide reel engaging elements or members arranged to engage a reel while in a lowered position so as to elevate the reel when swung upward. With the reel in this position it may be readily transported and cable may be unwound therefrom or wound thereon.

I provide means on the truck for revolving the reel for the purpose of winding cable thereon and unwinding cable therefrom; said means including a change of gear and a brake. A drum is also mounted on the truck and connected with said gearing for the purpose of winding a rope thereon when pulling cable either through ducts or aerial rings and for various other purposes.

Other features of the invention will be apparent from a perusal of the following specification and the invention will be more readily understood by reference to the accompanying drawings, in which an example of the invention is illustrated and wherein:

Figure 1 is a side view of the truck, the forward portion being illustrated in section and the rear portion in elevation,

Fig. 2 is a partial front elevation of the truck,

Fig. 3 is a plan view, and 55
Fig. 4 is a detail in section of the reel supporting and turning means.

In the drawings the numeral 1 designates a bed or horizontal frame which includes longitudinal outer beams 2 and parallel inner beams 3 spaced therefrom. The beams 2 and 3 are mounted in pairs on each side of the frame which is open at its rearward end to form a jaw or yoke to receive a cable reel. Near the center the beams are tied together by a transverse connection 4 and at the front end cross beams 5 complete the frame. A cross sill 6 carries the forward end of the frame and is in turn supported on a turning gear 7 which is mounted on an axle 8. The axle 8 is supported in ground wheels 9, while a reach bar 10 has diverging portions extending rearwardly and fastened to the under sides of the beams 3.

A bracket 11 depends from the rear extremity of each beam 3 and is united with a forwardly extending brace bar 12. From each outer beam a hanger 13 is supported. Each hanger is bent inward so as to confine a ground wheel 14 which has its trunnions bearing in said hanger and the bracket 11 and bar 12. The bars 12 extend forward each to a post 15 having its upper end fastened to one of the beams 3. At the intersection with the post the bar 12 is bent upward 75 and secured to one of the beams 3. Also at this point the bars are connected by a transverse channel member 16 which is also fastened to the lower ends of the posts. It is obvious that the rear wheels are properly 80 braced and held in position to sustain the load imposed. It will be seen that the greater portion of the rear of the frame between the beams 3 is free and unobstructed 85 so that a reel A may be readily received 90 therein.

For elevating the reel a pair of swinging quadrants 17 are mounted on the frame and attached to chains 18 which extend forward as shown, the peripheries of the quadrants 100 being grooved to receive the chains. The forward ends of the chains are wound about drums 19 mounted between the beams 2 and 3 on a transverse shaft 20. Each quadrant has a bearing boss 21 located at one end and the upward swing of the quadrant is limited 105 so that said boss will always be disposed rearward of the perpendicular with relation

to the pivot point of said quadrant. It will thus be seen that the load carried by the quadrants being sustained at the bearing bosses thereof will always swing the latter downward when the chains are paid off the drums 19. Cross bars 22 support the quadrants.

Reel clamping spiders 23 formed with hubs 24 and outwardly extending sleeves 25 are mounted in the bosses 21 as best shown in Fig. 4. The sleeves rotate in said bosses and the hubs bear against the same. The inner faces of the spiders are provided with spurs 26 which bite into the wooden sides of the reel. A transverse shaft 27 is employed for supporting the reel and rotating the same. This shaft is provided with a longitudinal key way 28 which receives keys 29 mounted in the hubs 24. On one side of the truck a gear 30 is fastened on the sleeve 25 and a jam nut 31 threaded on the end of the sleeve and bearing against the hub of the gear holds the sleeve and spider against lateral displacement. The spider on the opposite side is arranged to slide laterally to provide an adjustment for accommodating reels of different widths between the spiders.

In loading a reel the quadrants 17 are swung downward to the position shown in dotted lines in Fig. 1, the adjustable spider 23 having been moved laterally. The reel is rolled between the spiders and the quadrants are adjusted so that the hubs of the spiders register with the hub of the reel and permit the shaft 27 to be passed through the parts so that the keys 29 will enter the key way 28. That end of the shaft passing through the adjustable spider is screw-threaded to receive a nut 32 which bears against the end 40 of the sleeve 25 and the opposite end of the shaft is provided with a head 33 which bears against the end of the sleeve of the other spider. From this it will be seen that by screwing up the nut 32 the adjustable spider 45 will be moved toward the reel and sufficient pressure is finally exerted so that the reel is clamped firmly between the spiders and the spurs 26 embedded in the sides of the reel so that when said spiders are revolved 50 the reel must move therewith. By winding up the chains 18 the quadrants are swung upward and the reel elevated.

For revolving the shaft 20 a gear 34 is fixed thereon and meshes with a pinion 35 mounted on a shaft 36 disposed rearward of the shaft 20. The shaft 36 has squared ends for receiving a crank handle 37 by which said shaft may be revolved. A ratchet 38 is also mounted on the shaft 36 and engaged 60 by a pawl 39 loosely confined on the shaft 20. By means of the pawl and ratchet the drums 19 are held against revolution and the quadrants thus supported in any position to which they are elevated. It will be 65 noted that the contour of each quadrant is

such that a greater leverage is had with reference to the chain 18 at the beginning of the upward swing than at the end thereof, thus enabling the load to be more easily picked up.

For revolving the reel a pinion 40 is mounted on a shaft 41 under the gear 30 and meshes with said gear. The shaft 41 is supported on the beams 2 and 3 at one side of the frame and a similar shaft 42 is mounted on the beams at the opposite side. The quadrants are also loosely confined on these shafts which form their pivot points. A sprocket wheel 43 is mounted on the shaft 41 and made fast to the pinion. This sprocket 80 is driven by a chain 44 passing over a sprocket wheel 45 fixed on a shaft 47 which is parallel to a shaft 46. The shafts 20, 36, 46 and 47 are all disposed transversely of the frame and supported in suitable bearing 85 boxes on the beams 2 and 3. These shafts also have wrench ends for receiving the crank-handle 37.

On the shaft 47 a pair of gears 48 and 49, the latter being larger in diameter, are made fast between the beams on the side opposite that having the sprocket. The said gears are spaced apart and a pair of pinions 50 and 51 splined on the shaft 46 normally stand between the gears, the pinion 50 being designed to be meshed with the gear 49 and the pinion 51 with the gear 48. A yoke 52 embraces the pinions and is slid by a shifter 53, said pinions being fastened together. In revolving the reel the crank-handle 37 is applied to the shaft 46 and the latter revolved. The pinions 50-51 are engaged with one of the gears according to the ratio desired and the shaft 47 revolved, whereby the sprocket 45 is revolved. A 90 brake wheel 56 is fixed on the shaft 47 and surrounded by a brake band 55 which is tightened by a lever device 57 of the usual construction. An elongated drum 54 is also 95 fixed on the shaft 47.

It is obvious that a reel with cable thereon may be supported over a man-hole and the cable paid off as desired, or if the cable is to be strung aerially the truck can be positioned in line with the poles as desired. An empty reel can be elevated on the truck and cable wound thereon either from poles or underground ducts. In pulling in cable both aerially and underground it is necessary to use a rope and block and tackle and for this purpose the drum 54 is provided. The rope may be coiled about said drum and wound thereon, thus reducing the time and labor required in this operation. The many uses and advantages of this truck and its 115 equipment will be self evident to those skilled in the art.

What I claim, is:

1. In a truck of the character described, the combination with a portable frame, of 130

mechanism for elevating an electric cable reel to the frame and for revolving the same, said mechanism being mounted on the frame and including swinging clamping members between which the reel is received and clamped, reel revolving means carried by the clamping members, means mounted on the frame for elevating the clamping members, and means mounted on the frame for

10 operating the revolving means.

2. In a truck of the character described, the combination of a portable frame having supporting axles, a pair of elevating members hinged on the frame at a point removed 15 from the axles, a gear concentric with the pivot point of the elevating members, means mounted on the frame and connected with the gear for operating the same, a reel supporting shaft and reel engaging clamps connected thereby and mounted to revolve in 20 the elevating members, and a gear connected with one of the clamps and constantly in mesh with the first named gear.

3. In a truck of the character described, the combination of a portable frame, a reel elevating and revolving device mounted on the frame and comprising, a pair of quadrants hinged on the frame, flexible connection extending from the quadrants, winding means to which the connections are attached and whereby said connections are wound and unwound to swing the quadrants, a pair of spiders each having a sleeve mounted to revolve in the quadrants, a transverse shaft for supporting a cable reel between the spiders, said shaft passing through the spiders and their sleeves and having positive connection therewith for imparting revolution thereto, a gear carried by one of the quadrants for revolving the spiders and the 40 shaft, and a gearing mounted on the frame and meshing with the gear for imparting motion thereto.

In testimony whereof I affix my signature.

JAMES ALBERTS.
